CLAIM

The ornamental design for a ergonomic seat, as shown and described.

DESCRIPTION

FIG. 1 is a top perspective view of an ergonomic seat;
FIG. 2 is a bottom perspective view of the ergonomic seat shown in FIG. 1;

FIG. 3 is a front elevation view of the ergonomic seat shown in FIG. 1;

FIG. 4 is a rear elevation view of the ergonomic seat shown in FIG. 1;

FIG. 5 is a top plan view of the ergonomic seat shown in FIG. 1;

FIG. 6 is a bottom plan view of the ergonomic seat shown in FIG. 1;

FIG. 7 is a left-side elevation view of the ergonomic seat shown in FIG. 1; and,

FIG. 8 is right-side elevation view of the ergonomic seat shown in FIG. 1.

The broken lines illustrate portions of the ergonomic seat that form no part of the claimed design.

1 Claim, 8 Drawing Sheets
